U.S. PATENT DOCUMENTS

The ornamental design for a shoulder strap repositioner for vehicle seat belt assembly, as shown and described.

DESCRIPTION

D. 349,589	8/1994	York	.....	D29/100
D. 401,533	* 11/1998	Anscher	.....	D11/218
D. 408,961	5/1999	Myers	.....	D2/639
D. 424,785	* 5/2000	Conaway	.....	D2/639
3,941,404	3/1976	Otaegui-Ugarte	.....	D29/100
4,342,483	8/1982	Takada	.....	297/488
5,275,468	1/1994	Vacanti	.....	297/483

FIG. 1 is a three-dimensional view, generally of the front, of a shoulder strap repositioner for vehicle seat belt assemblies, showing my new design;

FIG. 2 is a front elevational view thereof;

FIG. 3 is a rear elevational view thereof;

FIG. 4 is a left side elevational view thereof, the right side being a mirror image;

FIG. 5 is a top plan view thereof; and,

FIG. 6 is a bottom plan view thereof.
